United States Patent Office.

N. L. BRUNDAGE AND B. DOWNING, OF PITTSSTON, PENNSYLVANIA.

Letters Patent No. 100,851, dated March 15, 1870.

IMPROVEMENT IN FUNNEL CAN-FILLERS.

The Schedule referred to in these Letters Patent and making part of the same.

To all whom it may concern:

Be it known that we, N. L. BRUNDAGE and B. DOWNING, of Pittston, in the county of Luzerne, and State of Pennsylvania, have invented a new and useful Improvement in Can-Fillers; and we do hereby declare that the following is a full, clear, and exact description thereof, which will enable others skilled in the art to make and use the same, reference being had to the accompanying drawings forming part of this specification.

This invention relates to a new and useful improvement in an article for filling cans in the process of preserving fruits, meats, vegetables, and all similar articles, by sealing them from the atmosphere, whereby the operation of filling the cans with the article to be preserved is greatly facilitated; and

The invention consists in a funnel-shaped filler provided with a suitable orifice, and with flanges or collars, as hereinafter more fully described.

In the accompanying drawings—

Figure 1 represents a vertical section of the filler through the line $z z$ of fig. 2.

Figure 2 is a view of the under or reverse side of the filler.

Similar letters of reference indicate corresponding parts.

A is the body of the filler.

B is the handle.

C is the orifice through which the article to be preserved is passed into the can.

On the bottom of the filler there are two flanges or collars D and E. The former sets down onto the top of the can and incloses its mouth; as seen in the drawing. The other enters the mouth of the can and delivers the fruit or other article into the body of the can, thus keeping the top of the can and packing perfectly clean and dry.

The flange or collar D which rests upon the can keeps the filler in place while the can is being filled.

The advantages of this article for the filling of cans are many, and will be obvious to all who have experienced the difficulties incident to the ordinary method.

Having thus described our invention,

We claim as new and desire to secure by Letters Patent—

1. The straight concentric collars or flanges D and E, the inner E extending below the outer D, in combination with the funnel-shaped body A of the can-filler, as and for the purpose herein set forth.

2. The combination of the funnel-shaped body A, orifice C, concentric flanges or collars D and E, and the handle B, arranged substantially as described and for the purposes set forth.

N. L. BRUNDAGE.
B. DOWNING.
